UNITED STATES PATENT OFFICE.

JAMES C. GORMAN, JR., OF MANSFIELD, OHIO, ASSIGNOR TO THE BARNES MANUFACTURING COMPANY, OF MANSFIELD, OHIO, A CORPORATION OF OHIO.

DOUBLE-ACTING FORCE-PUMP.

1,224,532.

Specification of Letters Patent.

Patented May 1, 1917.

Application filed August 9, 1916. Serial No. 114,022.

To all whom it may concern:

Be it known that I, JAMES C. GORMAN, Jr., a citizen of the United States, residing at Mansfield, in the county of Richland and 5 State of Ohio, have invented certain new and useful Improvements in Double-Acting Force-Pumps; and I do hereby declare the following to be a full, clear, and exact description of the invention, such as will enable others skilled in the art to which it 10 appertains to make and use the same.

This invention relates to pumps, and more particularly to power pumps of the type known as high pressure double acting 15 force pumps.

In pumps of this character the pump body and "jack", or that part of the casting which supports the gears and pinions for imparting motion to the piston, are usually made 20 separate, or the bearings are bolted on to the rear of the pump, and there is usually considerable movement between the pump and jack under high pressures, which movement is due no doubt to the play in the bolt holes 25 in the pump and jack through which they are bolted to the same base, and this play between the two units eventually allows the shafting of the gears and the piston rod of the pump to get out of alinement, causing 30 rapid wear.

One object of my invention is to provide a pump of the character referred to having the pump cylinder or casing and jack integral, whereby movement between the two 35 parts is entirely eliminated, thus insuring perfect alinement of the working parts of the pump at all times and decreasing the cost of repair parts, also eliminating considerable machine work on the rear end 40 of the pump, and thereby reducing the cost of manufacture, and also reducing wear and the cost of renewal of worn parts. Another object is to provide an integral pump cylinder or casing and jack adapted for a 45 double train of gears and pinions, or what is commonly known as a "double drive", which is very desirable for high pressure work, as it distributes the power more evenly to the cross head of the pump through the 50 connecting rods and thereby makes a better and more evenly balanced pump. Another object is to provide an integral pump body or casing and jack with a pump cylinder open at both ends, to adapt it to receive a 55 boring bar and provide supports therefor

at each end, together with a detachable plug for closing the open end adjacent to the jack, so that both ends of the cylinder being open it may be easily bored out and a brass lining easily rolled.

The invention will first be hereinafter more particularly described, with reference to the accompanying drawings, which form a part of this specification, and then pointed out in the claims at the end of the description.

In said drawings, Figure 1 represents a side elevation of so much of a double acting force pump as is necessary to illustrate my invention; the piston-actuating mechanism 70 being indicated in dotted lines;

Fig. 2 is a plan view of the same;

Fig. 3 is a longitudinal sectional elevation showing the pump body or casing in full lines and the jack in dotted lines; other 75 parts of the pump being omitted;

Fig. 4 is a cross section taken on the line 4—4 of Fig. 3;

Fig. 5 is a perspective view of the pump casing and jack viewed from the front end; 80

Fig. 6 is a perspective view of the pump casing and jack viewed from the rear end; and

Fig. 7 is a detail perspective view of the removable plug for closing the end of the 85 pump cylinder adjacent the jack.

Referring to said drawings, in which the same reference letters are used to denote corresponding parts in different views, the letter A may denote the pump body or casing and B the jack, or that part of the casting which supports the gears and pinions for imparting motion to the piston. The two parts A and B are formed or cast as one integral structure with a cylinder A¹, which 95 is open at both ends; and a removable plug A² is provided for closing the end thereof adjacent to the jack. The pump casing and jack are preferably cast integrally with supporting legs or standards which have apertured lugs or flanges on their lower ends to receive fastening bolts by which said parts may be firmly secured to the floor of the building or other foundation on which the pump is mounted. The pump body or casing, including the valve casing with water ways therein and means for seating suitable valves controlling said water ways, is formed with inlet and outlet openings a, and a¹, on opposite sides thereof, for connection with 100 105 110

inlet and discharge pipes, and with openings a^2 and a^3 in the top of the valve casing for inserting and affording access to the valves, and with an opening a^4 in its top, for the attachment of an air chamber; said openings being preferably formed co-incident with projections or bosses on the casing which, in the case of the inlet and outlet openings and the opening for the attachment of the air chamber, may be interiorly threaded for connection with the inlet and discharge pipes. The water ways a^5 and a^6 are in communication with said inlet and outlet openings and are controlled by suitable valves such as are ordinarily employed in pumps and which it is thought to be unnecessary to illustrate or describe. As shown, the rear standard or supporting leg of the pump casing constitutes the front supporting leg or end of the jack, which is cast with integral side walls b and a rear supporting leg or end portion b^1 and also with bearings b^2 and b^3 , for a plurality of shafts having gear wheels thereon for actuating the piston. Said bearings b^2 are formed integrally with said side walls b while the bearings b^3 are formed on rearwardly and upwardly inclined extensions of one of said side walls and of said rear end portion b^1 ; the latter being formed with a lateral extension on which one of said shaft bearings b^3 is formed; so as to separate it a sufficient distance from the other bearing to support a longer shaft than the one journaled in the bearings b^2 . The bearings b^2 , b^3 , as shown, are substantially semi-cylindrical in form and adapted for the attachment thereto of similarly shaped caps which fit over the gear shafts and confine them in their bearings. Thus constructed the jack provides efficient supporting bearings external to and integral with the pump cylinder and casing with provision for using a double drive piston-actuating mechanism having long-connecting rods, so as to evenly distribute the power from the engine to the piston rod and insure perfect alinement and even wearing of all parts with maximum efficiency and increased power. The piston actuating mechanism comprises a shaft journaled in the bearings b^2 and carrying at or near each end a gear wheel which meshes with a pinion on a counter-shaft journaled in the bearings b^3 and having a large gear wheel thereon which meshes with a pinion on the main driving shaft; the gear wheels on said first mentioned shaft each having a wrist-pin thereon for connection with one end of a pitman rod which extends past the other end of the pump casing and is pivotally connected with one end of a cross-head which has an intermediate connection with the piston rod, as shown in dotted lines in Figs. 1 and 2 of the drawings, thus providing long connecting rods and greatly in-

creasing the power over similar piston-actuating mechanisms with short connecting rods. To relieve the cylinder head from lateral strain, lugs a^7 , may be cast on the forward end of the pump cylinder or casing and in reamed holes formed in these lugs may be pressed and secured by suitable nuts the ends of steel rods which serve as guides for the cross-head, as shown in dotted lines in Figs. 1 and 2. Valve caps C, C, are removably secured on the pump casing over the openings for the valves therein by means of vertical bolts c which are secured in open-ended slots formed by bifurcated lugs or projections D on the pump casing and extend up through apertures in the projecting end portions of the caps; the head of the bolt being seated in a recess at the base of the lug so as to prevent the bolt from turning and permit the cap to be removed by loosening the nut and sliding the cap endwise to release the bolt. These valve caps have each a circular machined projection on the under side thereof which fits upon a correspondingly shaped and machined seat therefor surrounding the valve opening, so as to reduce the pressure on the packing between the valve cap and the pump.

The operation and advantages of my improved pump will be apparent to those skilled in the art to which the invention relates. The described construction adapts the jack to support a double train of gears, and as the jack is integral with the pump body or casing perfect alinement of the gear shafts and piston is assured, and all danger of these parts getting out of alinement is eliminated, while all wear on the gears, shafts, bearings, piston-rod and packing incident to the play allowed between the pump and jack when made separate, is avoided. This construction also enables me to arrange the pump and the gasoline engine which drives it in the same straight line, or in other words, to have the engine directly behind the pump, thus making a more compact, evenly balanced and complete pumping outfit, and one that occupies less space than pumps of the same general character as heretofore constructed. The pump cylinder being open at both ends permits a boring bar to be easily inserted and provides a support therefor at each end, so that the cylinder may be easily bored out and the brass lining for the same easily rolled. The open end of the cylinder adjacent the jack is closed by merely screwing the removable plug therein, while the other end may be closed by a head-plate through which the piston rod passes in the usual manner.

Having thus described my invention, what I claim as new and desire to secure by Letters Patent of the United States is:

1. An integral pump casing and jack; said jack being external to the pump and having

shaft supporting bearings thereon, and said casing comprising a pump cylinder open at both ends and having inlet and outlet openings on opposite sides thereof and valve 5 openings in its top together with water-ways connecting said openings and an opening for connection with an air chamber, all in one integral structure.

2. An integral pump body or casing and 10 jack; said jack being external to the pump and having shaft-supporting bearings thereon, and said body comprising a pump cylinder open at both ends and having valve-openings in its top and inlet and 15 outlet openings on opposite sides thereof; said openings being connected by suitable water-ways, and also having an opening in its top for connection with an air chamber.

3. An integral pump body or casing and 20 jack; said jack being external to the pump and having shaft-supporting bearings thereon, and said body comprising a pump cylinder open at both ends and having a removable cap or cover for the open end thereof 25 adjacent to said jack, and also having valve- openings in its top and an intermediate opening for connection with an air chamber, together with inlet and outlet openings on opposite sides thereof and connecting water- 30 ways.

4. A pump body or casing and a jack external thereto and integral therewith; said

jack having integral shaft-supporting bearings thereon, and said body comprising a pump cylinder open at both ends and integral 35 with a valve casing having valve openings in its top and inlet and outlet openings on opposite sides and water-ways in communication therewith and also having an opening in its top for connection with an air 40 chamber, together with a removable cap for closing the open end of the cylinder adjacent to said jack.

5. In combination, a pump casing and a jack external to said casing and integral 45 therewith; said jack having spaced bearings thereon for a plurality of shafts, and piston-actuating mechanism comprising a shaft on said jack having gear wheels thereon, a cross-head at the opposite end of said casing 50 having an intermediate connection with the piston-rod, pitman-rods on opposite sides of said casing each connecting one end of said cross-head with one of said gear wheels, and a second shaft on said jack geared to said 55 first named shaft and to a main driving shaft.

In testimony whereof I affix my signature in the presence of two witnesses.

JAMES C. GORMAN, Jr.
